HUM ELIMINATION MEANS

Emerick Toth, Cheverly, Md.

Application February 19, 1945, Serial No. 578,759

3 Claims. (Cl. 250—27)

(Granted under the act of March 3, 1883, as
amended April 30, 1928; 370 O. G. 757)

1

This invention is directed to the problem of extraneous voltages induced in circuits employing tubes with indirectly heated cathodes.

It is an object of the invention to eliminate such voltage.

It is a further object of the invention to eliminate induced voltages while permitting signal level gain variation within the elimination network.

The invention will be described with reference to the exemplary embodiments shown in the drawings, in which:

Figure 1 shows an application of the invention to an interstage coupling circuit,

Figure 2 shows in circuit diagram certain components of Figure 1,

Figure 3 shows an application of the invention to a variable gain interstage coupling circuit, and

Figure 4 shows in circuit diagram certain components of Fig. 3.

The circuit of Figure 1 comprises an interstage coupling circuit in which tube 1 is the driving tube and tube 2 is the driven tube. The driving tube is characterized in that its output is developed across a cathode load. In the circuit of Figure 1, tube 1 is a peak-limiting diode which is operative on the output of detector tube 3. Tube 3 is a diode having a load resistance comprising resistors 4 and 5, and is energized by a modulated intermediate or radio frequency signal introduced by transformer 6.

Anode 7 of the limiting diode is connected intermediately to the detector load resistance between resistors 4 and 5. Its cathode 8 is connected through series resistor 9 to the junction of the condenser 11 and series resistor 10 which are connected across the load resistance as shown.

Cathode 8 of diode 1 is provided with an indirect heater 12 which is normally energized by a low-frequency alternating current. In tubes embodying indirectly heated cathodes there is distributed capacity between the heater element and the cathode structure. In the usual application of such tubes, circuit means are employed wherein the impedance between the cathode itself and ground is very low at the frequency at which the heater is energized, and consequently the above mentioned residual capacity does not cause the development of an appreciable voltage swing at the heater current frequencies. In circuits in which the cathode is at relatively high impedance to ground, the capacitative current will develop a substantial A. C. voltage across the cathode load which appears in the output of the stage as a hum voltage. The circuit shown in Figure 1

is representative of the type of operation. Here heater 12 is energized through leads 13 and 14, lead 14 being grounded. With this connection there is an effective capacity connected between cathode 8 and lead 13 of the heater circuit.

The output of driving tube 1 is coupled through condenser 15 and appears across resistor 16. As the output includes the desired signal component and hum components induced from heater 12, these voltages are applied to amplifying tube 2 between control element 17 and ground, but the potential of cathode 18 is controlled so as to eliminate the undesired effects of the hum components added to the signal.

15 This is effected by providing a series resistor 19 connected to cathode 18, and additionally coupling cathode 18 to the ungrounded heater lead 13 through condenser 20. Condenser 20 is selected of suitable magnitude so that in combination with the distributed capacity between cathode 18 and its heater 21, cathode 18 will have induced thereon a voltage of substantially equal phase and magnitude with that of cathode 8 of tube 1. Consequently the hum voltage components which are coupled through to control element 17 of tube 2 do not cause a resulting shift in the grid-cathode potential of amplifying tube 2.

30 The operation of the circuit of Figure 1 will be more apparent from an inspection of Figure 2, in which certain circuit elements in which the hum and signal components are present are shown in bridge form. The hum voltage may be considered to be introduced at terminals 22 and 35 23 of Figure 2. Condenser 21 constitutes the distributed cathode-heater capacity of diode 1. Inasmuch as the reactance of condenser 11 may be substantially neglected in view of the magnitude of resistance 9, and condenser 15 has very

40 low reactance with comparison to the resistance 16, a suitable value for condenser 20 (which forms one arm of the bridge) may be selected to establish zero voltage between control element 17 and cathode 18 of tube 2 with respect to the undesired hum voltage. In this connection it will be noted that condenser 20 as shown in Figure 2 may be considered to include the distributed capacity between cathode 18 of tube 2 and its heater 21. The bridge arrangement formed by the inclusion

45 of condenser 20 is in balance as regards the undesired hum voltage but out of balance as regards the desired signal voltage, so that the desired signal is unaffected by the bridge.

50 The circuit shown in Figure 3 is similar to that of Figure 1 but illustrates the employment of the

invention in connection with a circuit where variation of the desired signal input level to control element 17 is required without substantially affecting the hum voltage balance.

In order to obtain signal level variations in the circuit of Figure 3, voltage divider 25 is coupled to condenser 15 and is connected also to cathode 18 of tube 2. The signal delivered from voltage divider 25 is coupled through condenser 26 to resistor 16 connected with control element 17 of tube 2. The grid-cathode signal on tube 2 is determined by the adjustment of voltage divider 25.

Through the operation of condenser 20, however, the induced hum voltages are prevented from affecting the grid-cathode potential in tube 2. This may be better seen from the diagram shown in Figure 4. Here, as in Figure 2, the hum voltages may be considered to be supplied at terminals 22 and 23. Condenser 20 again is connected so that no voltage of heater supply frequency is developed across the bridge diagonal consisting of condenser 15 and voltage divider 25. Consequently, inasmuch as the value of resistance 16 is much greater than the impedance of condenser 26, control element 17 of the tube 2 may be considered to be connected directly to the voltage divider. No hum voltage components are developed across the grid-cathode input of tube 2 at any setting of the volume control voltage divider 25 provided that the value of resistor 16 is large compared to resistor 19. This is normally the case and the hum voltage component will be substantially eliminated from the output circuit of tube 2.

It will be understood that the embodiments shown and described are exemplary only and are not to be considered as limiting the invention, the scope whereof is defined in the appended claims.

The invention described herein may be manufactured and used by or for the Government of the United States of America for governmental purposes without the payment of any royalty thereon or therefor.

I claim:

1. An interstage transmission circuit comprising a driving tube having a cathode and a heater therefor, said heater having a capacity in relation to said cathode and being operative on energization to effect a hum potential variation thereof, means for controlling the cathode potential in accordance with a control signal, an impedance driven by the cathode, a second tube having a control element and cathode, an impedance in series with the second tube cathode, means connecting the control element with the first tube cathode, and a capacitor connected between the second tube cathode and the first

tube heater operative to drive said second cathode in substantially the same potential phase and amplitude as the hum potential variation of the first tube cathode.

- 5 2. An interstage transmission circuit comprising a driving tube having a cathode and a heater therefor, said heater having a capacity in relation to said cathode and being operative on energization to effect a hum potential variation thereof, 10 means for controlling the cathode potential in accordance with a control signal, a resistance connected to the cathode, a second tube having a control element and a cathode, a resistance in series with the second tube cathode, a capacitor connected between the second tube cathode and the first tube heater operative to drive said second cathode in substantially the same potential phase and amplitude as the hum potential variation of the first tube cathode, a resistance connected 15 between the first and second cathodes, and means for adjustably coupling the control element to said last mentioned resistance.

- 20 3. A limiting detecting and amplifying circuit including a diode having a load resistance, means 25 for introducing a signal in series with said load resistance, a condenser connected to the positive end of the load resistance, a series resistor connecting the condenser to the other end of the load resistance, a resistance connected to the 30 junction of the condenser and series resistance, a second diode having a cathode connected to the last mentioned resistance, an anode connected to an intermediate point on the load resistance, and a heater for its cathode, said heater having 35 a capacity in relation to said cathode, an amplifying tube including a cathode and a control element, a resistor connecting said last mentioned cathode with the positive end of the load resistance, means coupling the control element to the 40 cathode of the second diode, and a condenser connected between the amplifying tube cathode and the second diode heater operative to cause a similar potential variation in said cathode as is established in the second diode heater on A. C. 45 heater operation.
